UNITED STATES PATENT OFFICE.

THOMAS TEMPLE, OF FORT PLAIN, NEW YORK.

CARDING-MACHINE FEEDER.

1,297,607.

Specification of Letters Patent. Patented Mar. 18, 1919.

Application filed April 29, 1918. Serial No. 231,456.

To all whom it may concern:

Be it known that I, THOMAS TEMPLE, a citizen of the United States, residing at Fort Plain, in the county of Montgomery and State of New York, have invented certain new and useful Improvements in Carding-Machine Feeders; and I do declare the following to be a full, clear, and exact description of the invention, such as will enable others skilled in the art to which it appertains to make and use the same.

My invention relates to improvements in carding machine feeders and more particularly to a novel "pusher" which is movable to and from the "packer" operating over the feed apron or table. Heretofore, the pusher has been in the form of a vertical plate which maintained its vertical position at all times, served in no manner to guide the carding from the automatic scales onto the feed table, and often allowed some of the material to be wasted by dropping in rear rather than in advance of the pusher. Furthermore, independent operating mechanisms have been required for the packer and pusher.

My invention has for its principal object to provide a pivoted pusher constantly maintained in position to prevent passage of material behind the same and to guide such material onto the feed table, the lower edge of the device being inclined outwardly for this purpose.

A further object is to provide an arrangement whereby the operating mechanism of the packer may be used also to synchronously operate the pusher.

With the foregoing general objects in view, the invention resides in the novel features and arrangement of parts hereinafter fully described and claimed, the descriptive matter being supplemented by the accompanying drawing wherein:

Figure 1 is an end elevation of a carding machine feeder constructed in accordance with the present invention; and

Fig. 2 is a perspective view of the pusher detached.

In the drawing above briefly described, the numeral 1 designates a carding machine feeder including an automatic weighing device 2, a feed apron or table 3 upon which the carding is deposited by the weighing device 2, a packer 4 at the outer edge of the table 3, and means for operating said packer. This operating means is shown as consisting of vertical slotted arms 5 rising from the piv-

otal mounting of the packer, pitmen 6 pivoted to arms 5 by bolts passing through the slots 7 thereof, and eccentrics or the like 8 for reciprocating said pitmen. But one of the parts 5, 6 and 8 are shown, but it is to be understood that they are duplicated on the other side of the machine.

The improved pusher 9 is formed of a vertical sheet metal plate depending from a horizontal rock shaft 10 which is mounted in suitable bearing brackets 11 secured to the machine 1. The shaft 10 is spaced inwardly from the path on which the carding drops from the weighing device 2 onto the table 3, so that there is no danger whatever of any of such carding falling in rear of the pusher, and in order to effectively guide the material onto the feed table, the lower edge of the pusher 9 is turned outwardly at 12 and positioned over the inner edge of the table. This also prevents the accumulation of any material between the lower edge of the pusher and the inner edge of the table as will be clear from Fig. 1. Another feature of great importance is that the shaft 10 is located above the plane reached by the two outwardly swinging bottom sections of the weighing device 2, when said sections are opened as shown in dotted lines in Fig. 1. One of the sections, designated by the numeral 13, swings against the outer face of the pusher 9 and thus, even though the upper edge of this pusher were not located exactly as shown, none of the carding could pass behind the pusher or collect on its upper edge.

For the purpose of operating the pusher 9 without the necessity of employing a mechanism separate from that utilized for operating the packer 5, and for synchronizing the movement of said packer and pusher, the rock shaft 10 is provided with depending arms 14, and these arms are connected by links or pitmen 15 with the crank arms 5 of the packer. It thus follows that the operating mechanisms of said packer will in turn actuate the pusher 9 to feed the carding along the feed table 3 to be operated upon by said packer.

From the foregoing, taken in connection with the accompanying drawing, it will be obvious that although my invention is of simple and inexpensive nature, it will be much more desirable than the constructions now in use, and since probably the best results are obtained from the several details shown and from the arrangement of parts

disclosed, these features are preferably employed, but within the scope of the invention as claimed, considerable latitude is allowed for making such minor changes as occasion may dictate.

5 I claim:

1. The combination with a carding machine feed table, a packer over said table, a weighing device spaced over said table, and 10 an apron for guiding the carding from said weighing device onto said table; of means for moving said apron toward said packer to feed the carding beneath the latter.
2. In a feeder for carding machines, the 15 combination with the horizontal feed table, the pivotally mounted packer above the outer portion of said table, a vertical arm extending from said packer, a pitman connected to said arm for operating the same 20 to actuate said packer, and an automatic weighing device above said table for depositing the carding thereon; of a pusher for feeding the carding along said feed table toward said packer, and a second pitman 25 connecting said pusher with said vertical arm to operate the former from the latter.
3. In a feeder for carding machines, the 30 combination with the horizontal feed table, a packer operating above the outer portion of said table, and an automatic weighing device above said table including a downwardly and laterally swinging bottom section; of a substantially vertical pusher pivotally mounted at its upper edge and having

35 said edge disposed substantially in the lateral path of said bottom section to guide the carding onto said feed table, and means for operating said pusher to feed the carding along the feed table toward said packer.

4. A structure as specified in claim 2, both 40 pitmen being adjustable along said vertical arm to vary the strokes of said packer and pusher.

5. In a feeder for carding machines, the 45 combination with the horizontal feed table, the pivotally mounted packer above the other portion of said table, the vertical arm rising from said packer, the pitman connected to said arm for operating the same to actuate said packer, and the automatic 50 weighing device above said table for depositing the carding thereon; of a pusher mounted pivotally at its upper edge for feeding the carding along the feed table toward said packer, a crank arm depending from the 55 pivot of said pusher, and an additional pitman connecting said last named crank arm with the aforesaid crank arm of said packer.

6. A structure as specified in claim 5, both 60 pitmen being adjustable along said vertical arm to vary the strokes of said packer and pusher.

In testimony whereof I have hereunto set my hand.

THOMAS TEMPLE.
